UNITED STATES PATENT OFFICE.

VINTON E. SISSON, OF CHICAGO, ILLINOIS, ASSIGNOR TO WALTER P. MURPHY, OF CHICAGO, ILLINOIS.

DIAPHRAGM-PLATE BUFFER-SPRING FOR RAILWAY-CAR VESTIBULES.

1,247,340.

Specification of Letters Patent. Patented Nov. 20, 1917.

Application filed December 4, 1916. Serial No. 134,844.

To all whom it may concern:

Be it known that I, VINTON E. SISSON, a citizen of the United States, residing at Chicago, in the county of Cook and State 5 of Illinois, have invented certain new and useful Improvements in Diaphragm-Plate Buffer-Springs for Railway-Car Vestibules, of which the following is a specification.

My invention relates to a buffer spring 10 adapted to be interposed between the diaphragm face plate of a railway car vestibule and the end of the car, for the purpose of maintaining the plate in engagement with the corresponding element of the vestibule 15 of the adjacent car and returning the plate to its normal position parallel to the end of the car after it has been displaced—for example, when the train rounds a curve. A device of this type is described and claimed 20 in a patent to Frank G. Fowler, #1,019,777, patented March 12th, 1912.

One of the objects of my invention is to provide means for attaching the spring to the face plate, which will obviate the necessity 25 of perforating, and thereby weakening, the spring leaves, as must be done if the springs be bolted or riveted to the plate.

Another object of the invention is to provide retaining devices for the extremities of 30 the spring, adapted to be firmly secured to the end wall of the car and furnished with rubbing plates for the ends of the spring to bear against, arranged so that they can be readily removed when worn out.

35 It is customary to employ in this connection a compound semi-elliptical spring, the center portion of which is rigidly attached to the face plate, while the extremities have a sliding engagement with the ends of the 40 car, and this is the arrangement which is herein shown and described. It would be possible, though for reasons of convenience not desirable, to reverse the position of the 45 spring, fastening the center portion to the car ends and engaging the extremities with the face plate.

Changes in details of construction might be made without departure from the intent and purpose of my invention as defined in 50 the appended claims.

The invention is illustrated in the accompanying drawings wherein

Figure 1 is a fragmentary plan view of the ends of adjoining vestibule railway cars

fitted with the diaphragm face plate buffer 55 springs and attachments of my invention.

Fig. 2 is a sectional view on line 2—2 of Fig. 1.

Fig. 3 is a fragmentary sectional plan on an enlarged scale taken on line 3—3 of 60 Fig. 2.

Fig. 4 is a view in perspective of one of the bracket members forming part of the means for retaining the extremities of the spring in sliding engagement with the end 65 wall of the car.

Fig. 5 is a similar view of one of the removable rubbing plates forming a part of said retaining means, and

Fig. 6 is a similar view of a part of the 70 means employed for rigidly securing the center portion of the spring to the face plate.

Like characters of reference designate like parts in the several figures of the drawings. 75

Referring to the drawings, the end wall of the car is shown at 10 and the diaphragm face plate at 11. 12 is the buffer spring consisting preferably of a compound elliptical leaf spring, the leaves of which are secured 80 together by a band 13 which is shrunk and pressed upon them so as to hold the leaves against movement with respect to each other. Secured to the face plate 11, for example by rivets 14, is a channel-shaped bracket 85 member 15, forming a seat for the center portion of the spring. 16 is a retaining device adapted to fit into the bracket member 15 outside of the spring and formed with vertical perforations 17 made to aline with 90 corresponding perforations in the bracket member, whereby the retaining member may be held pressed against the spring by bolts 18. The retaining member is formed with shoulders or abutments 19 adapted to stand 95 on either side of and close to the edges of the spring band 13. The engagement between the shoulders and the band prevents lengthwise movement of the spring through the bracket 15.

100 Each end of the master leaf 20 of the spring is bent over as indicated at 21 and is retained in sliding engagement with the end wall of the car by a retaining device constructed as follows: 22 is a bracket member secured to the end wall of the car—for example, by rivets 23 and provided with a pair of outstanding webs 24—24 formed

with perforations 25 for a bolt 26 adapted to be engaged by the hook or bent over portion 21 of the spring. Between the bracket member and the end of the spring is interposed a rubbing plate 26^a formed with outstanding flanges 27 which preferably diverge a trifle, as manufactured, so that they are compressed with spring pressure when the rubbing plate is forced into place in the bracket. The rubbing plate is also preferably formed with backwardly projecting ribs 28 engaging the edges of the bracket member. The flanges 27 of the rubbing plate are formed with perforations 29 so that the rubbing plate is held in position in the bracket member by the bolt 26 above mentioned. The rubbing plate may, however, be readily removed when it is worn out without detaching the bracket from the end of the car. The manner in which the members 16 and 26^a are constructed and applied so as to interlock with the spring band 13 and the bracket 22, respectively, prevents unnecessary movement between the various parts of the spring holding devices and thereby prevents the knocking or rattle which would be present if the parts were loosely engaged.

I claim:

30. 1. The combination with the end wall and diaphragm face plate of a vestibuled railway car, of a spring arranged between the aforesaid structural elements of the car, secured to one of them and having a sliding engagement with the other, and a retaining device providing said sliding engagement, which is fixed to one of said car elements and has a removable rubbing plate against which the spring bears.
40. 2. The combination with the end wall and diaphragm face plate of a vestibuled railway car, of a spring arranged between the aforesaid structural elements of the car, secured to one of them and having a sliding engagement with the other, and a retaining device providing said sliding engagement, which is fixed to one of said car elements and comprises outstanding webs and a rubbing plate against which the spring bears, removably engaged between said webs.
50. 3. The combination with the end wall and diaphragm face plate of a vestibuled railway car, of a spring arranged between the aforesaid structural elements of the car, secured to one of them and having a sliding engagement with the other, and a retaining device providing said sliding engagement, which is fixed to one of said car elements and comprises outstanding webs and a rubbing plate against which the spring bears having flanges removably engaged with said webs.
60. 4. The combination with the end wall and diaphragm face plate of a vestibuled railway car, of a spring arranged between

the aforesaid structural elements of the car, secured to one of them and having a sliding engagement with the other, a retaining device providing said sliding engagement, which is fixed to one of said car elements and comprises outstanding webs and a rubbing plate against which the spring bears, and a bolt with which the spring engages extending through said webs and flanges.

5. The combination with the end wall 75 and diaphragm face plate of a vestibuled railway car, of a spring arranged between the aforesaid structural elements of the car, secured to one of them and having a sliding engagement with the other, a U-shaped 80 bracket member secured to said last named car element and a U-shaped rubbing plate removably secured within said bracket member.

6. The combination with the end wall 85 and diaphragm face plate of a vestibuled railway car, of a spring arranged between the aforesaid structural elements of the car, secured to one of them and having a sliding engagement with the other, a U-shaped 90 bracket member secured to said last-named car element, a U-shaped rubbing plate arranged within said bracket member, and a bolt securing said plate to said bracket member and adapted to be engaged by the 95 end of said spring.

7. The combination with the end wall and diaphragm face plate of a vestibuled railway car, of a spring arranged between the aforesaid structural elements of the car, 100 secured to one of them and having a sliding engagement with the other, a U-shaped bracket member secured to said last named car element, a U-shaped rubbing plate having sliding, diverging flanges which are 105 bent when the plate is fitted into said bracket member, and means for securing the same in place in said bracket member.

8. The combination with the end wall and diaphragm face plate of a vestibuled railway car, of a spring arranged between the aforesaid structural elements of the car, secured to one of them and having a sliding engagement with the other, a bracket member secured to said last named car element, 115 and a U-shaped rubbing plate secured within said bracket member provided with ribs engaging the edges of said bracket member.

9. The combination with the end wall and diaphragm face plate of a vestibuled railway car, of a compound leaf spring interposed between the aforesaid structural elements of the car, a band surrounding and firmly engaging the spring leaves, and means for rigidly securing said spring to 125 one of said car elements, which means is provided with abutments which lie along opposite edges of the band to prevent lengthwise movement of the spring.

10. The combination with the end wall 130

and diaphragm face plate of a vestibuled railway car, of a compound leaf spring interposed between the aforesaid structural elements of the car, a band surrounding and firmly engaging the spring leaves, means for rigidly securing the spring to one of said car elements, comprising a spring seat, a retaining device for holding the spring in the seat, and abutments which lie along opposite edges of the band to hold the spring from longitudinal movement.

11. The combination with the end wall and diaphragm face plate of a vestibuled railway car, of a compound leaf spring interposed between the aforesaid structural elements of the car, a band surrounding and firmly engaging the spring leaves, means for rigidly securing the spring to one of said car elements, comprising a spring seat, a retaining device for holding the spring in the seat, and abutments on said retaining device which lie along opposite edges of the band to hold the spring from longitudinal movement.

12. The combination with the end wall and diaphragm face plate of a vestibuled railway car, of a compound leaf spring interposed between the aforesaid structural elements of the car, a band surrounding and firmly engaging the spring leaves, a channel-shaped bracket on one of said car elements forming a spring seat, a retaining device fitting into said bracket outside of the spring, one of said members being provided with abutments adapted to engage the opposite edges of the spring band, and bolts extending through said bracket and retaining device.

taining device fitting into said bracket outside of the spring, and bolts extending through said bracket and retaining device. 35

13. The combination with the end wall and diaphragm face plate of a vestibuled railway car, of a compound leaf spring interposed between the aforesaid structural elements of the car, a band surrounding and firmly engaging the spring leaves, a channel-shaped bracket on one of said car elements forming a spring seat, a retaining device fitting into said bracket outside of the spring, one of said members being provided 40 with abutments adapted to engage the opposite edges of the spring band, and bolts extending through said bracket and retaining device.

14. The combination with the end wall and diaphragm face plate of a vestibuled railway car, of a compound leaf spring interposed between the aforesaid structural elements of the car, a band surrounding and firmly engaging the spring leaves, a channel-shaped bracket on one of said car elements forming a spring seat, a retaining device fitting into said bracket outside of the spring, which is provided with shoulders 55 bearing against the opposite edges of the spring band, and bolts extending through the bracket and retaining device.

VINTON E. SISSON.
